TEMPERATURE INDICATING INSTRUMENT

Samuel E. O'Connell, New York, N.Y., assignor, by mesne assignments, to A-T-O Inc., Cleveland, Ohio, a corporation of Ohio

Filed Feb. 3, 1969, Ser. No. 15,613

Term of patent 14 years

Int. Cl. D10—07

U.S. Cl. D52—7

FIG. 1 is a perspective view of a temperature indicating instrument embodying the design of this invention;

FIG. 2 is a top plan view of the instrument of FIG. 1;

FIG. 3 is a side elevational view of the instrument of FIG. 1 on an enlarged scale with portions of the outer case broken away showing the rotatable indicating element; and

FIG. 4 is a bottom plan view of the instrument of FIG. 1,

The dominant features of this design reside in the portions shown in full lines.

I claim:

The ornamental design for a temperature indicating instrument, as shown and described.
